UNITED STATES PATENT OFFICE.

CLARENCE E. DOYLE, OF WASHINGTON, DISTRICT OF COLUMBIA, ASSIGNOR TO HUTCHINSON EGG-CASE FILLER COMPANY, OF HUTCHINSON, KANSAS.

RECEPTACLE-CLOSURE.

1,347,446.

Specification of Letters Patent.

Patented July 20, 1920.

Application filed February 4, 1920. Serial No. 356,273.

To all whom it may concern:

Be it known that I, CLARENCE E. DOYLE, a citizen of the United States, residing at Washington, in the District of Columbia, have invented a new and useful Improvement in Receptacle-Closures, of which the following is a specification.

The object of the invention is to provide a simple and relatively inexpensive means adapted for application as an attachment to boxes, packages and receptacles particularly of the paste-board and card-board type designed as shipping containers for salt, spices, baking-powder and other granular and powdered substances, and more especially those designed for domestic use, whereby the quantitative discharge of the contents of the receptacle may be facilitated while insuring the effective protection there- 20 of from dust and atmospheric deterioration during the intervals between the periods of use, and thus to provide a convertible closure and dispensing spout for use in connection with an outlet orifice which may be formed in a wall of such receptacle or container, and to devise a construction for the purpose of which the blank may be stamped in one operation from sheet metal and may be permanently and at the same time mov- 25 ably mounted upon the receptacle with the minimum effort and expenditure of time as to the assembling agency and without necessitating the exercise of a high degree of skill when performed manually.

With these objects in view, the invention consists in a construction and combination of instrumentalities of which a typical embodiment is illustrated in the accompanying drawing, wherein—

Figure 1 is a view of the device in its normal or closed position in relation to a receptacle.

Fig. 2 shows the same adjusted for use as a spout.

Fig. 3 is a view taken from the inside of the receptacle.

Fig. 4 is a view of the blank.

The preferred form of the device consists of sector-shaped cover and guide wings 50 10 and 11 produced from a substantially semi-circular blank (Fig. 4) by bending on a radial fold line 12. The free radial boundary 13 of the cover wing, constituting the portion of the diametrical edge extending in one direction from the intersection of

the fold line, is designed as a bearing or hinge edge to be seated upon the exterior surface of a wall 14 of a receptacle adjacent to an outlet opening 15 provided therein, and projecting from said edge for penetration of the receptacle wall are ears or extensions 16, 17, adapted for contact with the inner surface of said wall, respectively, in the open and closed positions of the cover wing. To this end one of the ears,—as for example that designated as 16—is of such dimensions as to be pliable, so that after the ears have penetrated the wall of the receptacle, one of them may be bent to extend substantially perpendicular to the other. These ears are preferably arranged remote from the plane of the fold line 12, or near the outer arcuate edge of the cover wing.

The radial free edge 18 of the guide wing carries an ear or extension 19, also bendable to a position perpendicular to the plane of the wing and serving by contact with the inner surface of the receptacle wall to hold that end of the hinge or bearing edge of the 75 cover wing which is near the fold line in an effectively seated position on the receptacle wall, in both the open and closed positions of the device. The guide wing which extends through and operates in the 80 outlet opening of the receptacle wall is also provided with a stop ear or extension 20, to engage the inner surface of the wall and limit the hinge or swinging movement of the cover wing, when the attachment is ex- 85 tended as in Fig. 2, to serve as a spout.

The ears or extension on the hinge edge of the cover wing may be formed as shown of a single tongue, terminally reduced to facilitate penetration of the receptacle wall 90 and split to provide for separation after the penetration has been effected.

What I claim is:

1. A convertible closure and spout for receptacles having angularly disposed cover 100 and guide wings, of which the former is adapted to be hingedly seated at one edge on a receptacle wall adjacent to an opening therein, and wall penetrating extensions on the seated edge of the cover wing for contact with the inner surface of the penetrated wall respectively in the closed and open positions of the cover wing.

2. A convertible closure and spout for receptacles having angularly disposed cover 110

and guide wings, of which the former is adapted to be hingedly seated at one edge on a receptacle wall adjacent to an opening therein, and wall penetrating extensions on the seated edge of the cover wing and extending respectively substantially in the direction of and at an angle to the plane of said wing.

3. A convertible closure and spout for receptacles having angularly disposed cover and guide wings, of which the former is adapted to be hingedly seated at one edge on a receptacle wall adjacent to an opening therein, and wall penetrating extensions on the seated edge of the cover wing, one of said extensions being in contact with the inner surface of the wall when the cover wing is in the open position.

4. A convertible closure and spout for receptacles having angularly disposed sector-shaped cover and guide-wings of which the latter is provided at its free radial edge with a lateral ear located near the angular junction line of the wings while the former is provided at its free radial edge with a plurality of ears, one of which is arranged remote from said angular junction line and is disposed substantially perpendicular to the plane of the wing.

30 5. As an article of manufacture a blank for a convertible closure and spout for receptacles, having a substantially semicircular body foldable on a radial crease line to form quadrant-shaped wings and provided 35 at the diametrical free edge; at each side of the fold line, with a plurality of extension ears.

6. As an article of manufacture a blank for a convertible closure and spout for re-

ceptacles, having a substantially semicircular body foldable on a radial crease line to form quadrant-shaped wings and provided at the diametrical free edge at each side of the fold line with groups of extensions forming ears, and one ear of each group being pliable for deflection to a plane perpendicular to the plane of the adjacent portion of the body.

7. As an article of manufacture a blank for a convertible closure and spout for receptacles, having a substantially semicircular body foldable on a radial crease line to form quadrant-shaped wings and provided at the diametrical free edge at each side of the fold line with ears or extensions which on one wing are remote from and on the other are respectively adjacent to and remote from said fold line, and one each of the ears at opposite sides of the fold line being bendable to a plane perpendicular to the plane of the wing by which it is carried.

8. The combination with a receptacle having an outlet opening in the wall thereof, of a closure for said opening having angularly related cover and guide wings provided with radial free edges of which that of the cover wing is seated upon the exterior surface of the receptacle wall adjacent to the opening, the guide wing being extended through the receptacle wall and having an arcuate edge concentric with the seated edge of the cover wing, each of said wings at its radial edge having ear extensions and those of the cover wing extending respectively substantially in the direction of and perpendicular to the plane of said wing.

CLARENCE E. DOYLE.
